(57) **CLAIM**

The ornamental design for a combined micro tube and cap, as shown and described.

DESCRIPTION

FIG. 1 is a perspective view of a combined micro tube and cap showing our new design;

FIG. 2 is a top view thereof;

FIG. 3 is a front view thereof;

FIG. 4 is a bottom view thereof;

FIG. 5 is a right view thereof; the left side view thereof being a mirror image;

FIG. 6 is a back view thereof;

FIG. 7 is a partial large view of plan view thereof;

FIG. 8 is a front view with cap closed thereof;

FIG. 9 is a perspective view of a second embodiment of a combined micro tube and cap showing our new design;

FIG. 10 is a top view thereof;

FIG. 11 is a front view thereof;

FIG. 12 is a bottom view thereof;

FIG. 13 is a right view thereof; the left side view thereof being a mirror image;

FIG. 14 is a back view thereof;

FIG. 15 is a partial large view of plan view thereof; and,

FIG. 16 is a front view with cap closed thereof.

The broken lines in the drawing views represent unclaimed portions of the combined micro tube and cap and form no part of the claimed design.
